(57) **CLAIM**

The ornamental design for a handle for a multipurpose hand tool, as shown and described.

DESCRIPTION

FIG. 1 is an isometric view from the upper right front of a handle for a multipurpose hand tool including our new design, wherein the heads of pivot pins and portions of a blade latch mechanism shown in broken line are included merely for illustrative purposes and form no part of the claimed design;

FIG. 2 is a right side elevational view thereof, wherein the heads of pivot pins and portions of a blade latch mechanism shown in broken line are included merely for illustrative purposes and form no part of the claimed design;

FIG. 3 is a top plan view thereof, wherein the portions of pivot pins and of a blade latch mechanism shown in broken line are included merely for illustrative purposes and form no part of the claimed design;

FIG. 4 is a bottom plan view thereof, wherein the portions of pivot pins and of a blade latch mechanism shown in broken line are included merely for illustrative purposes and form no part of the claimed design;

FIG. 5 is a left side elevational view thereof, wherein the heads of pivot pins and portions of a blade latch mechanism shown in broken line are included merely for illustrative purposes and form no part of the claimed design;

FIG. 6 is a rear end elevational view thereof, wherein the portions of a blade latch mechanism shown in broken line are included merely for illustrative purposes and form no part of the claimed design; and,

FIG. 7 is a front end elevational view thereof, wherein the portions of a blade latch mechanism shown in broken line are included merely for illustrative purposes and form no part of the claimed design.
